UNITED STATES PATENT OFFICE.

EUGENE CRINON, OF VASSALBORO, MAINE.

PICKER-STAFF AND SWEEP-STICK CONNECTION FOR LOOMS.

SPECIFICATION forming part of Letters Patent No. 793,182, dated June 27, 1905.

Application filed August 12, 1902. Serial No. 119,435.

To all whom it may concern:

Be it known that I, EUGENE CRINON, a citizen of the Republic of France, residing at Vassalboro, in the county of Kennebec and State 5 of Maine, have invented certain new and useful Improvements in Picker-Staff and Sweep-Stick Connections for Looms, of which the following is a specification.

My invention relates to looms, and especially to the mounting of the picker-staff and connecting it with the sweep-stick.

The objects of my invention are to provide a very durable lug-strap for the end of the sweep-stick that shall give a very substantial 15 buffer in its striking end, to dispense with the necessity for perforating the picker-staff, to attach thereto the leather strap usually employed to regulate the power of the shuttle, and to supply in lieu thereof a rod for regulating the distance between the sweep-stick 20 and the pivotal point of the picker-staff.

Additional advantages of my invention will more fully appear hereinafter and by reference to the accompanying drawings, in which—

Figure 1 is a view in elevation of a part of a loom, showing my improvement in position; Fig. 2, a plan view of the lug-strap, and Fig. 3 a view of a portion of the sweep-stick and a vertical section of the lug-strap.

Referring to the drawings, in which similar reference characters indicate corresponding parts throughout the several views, A represents the frame of a loom; B, the sweep-stick; C, the lug-strap secured to the end of the sweep-stick, and D the picker-staff pivoted by means of the bolt E to the lay-beam E'.

The lug-strap C is made of a flat steel bar, bent to form a loop C' to receive the picker-staff D, the ends of said loop being secured to 40 the end of the sweep-stick B by means of bolts F.

G is a bolt inserted through the loop C' and having a sleeve H thereon. The purpose of the bolt G is to limit the swing of the picker-staff when striking the shuttle. A buffer-pad 45 I, made of leather and having a face-plate K of metal, is secured in the end of the loop C' by means of a rivet L.

M represents a metal strap having its lower end pivoted on the bolt E and its upper end 50 secured to the bolt G through one of the holes N. The purpose of the strap M is to adjust the height of the sweep-stick from the base of the loom, and thus increase or decrease the striking power and the length of swing of the 55 picker-staff.

Having thus described my invention, what I claim is—

In a loom, the combination with the picker-staff, and the sweep-stick, of a strip of flat 60 metal bent to form a U-shaped loop secured to the end of the sweep-stick, a buffer-pad secured in the bent portion of the loop consisting of a cushion of leather and a face-plate of rigid material, said pad being secured to the 65 loop by means of a bolt passing through said pad and loop intermediate of the ends of said pad, the picker-staff mounted in said loop and adapted to strike the ends of said pad, a bolt passed through said loop on the side of said 70 picker-staff opposite to said pad, and a supporting-rod suitably pivoted and having a series of holes adapted to register with said bolt, substantially as shown and described.

In testimony whereof I hereto affix my signature in the presence of two witnesses.

EUGENE CRINON.
